UNITED STATES PATENT OFFICE.

WILLIAM P. O'HARA, OF CINCINNATI, OHIO.

SAMPLING-TUBE OR LIQUOR-THIEF.

SPECIFICATION forming part of Letters Patent No. 275,694, dated April 10, 1883.

Application filed June 5, 1882. (No model.)

To all whom it may concern:

Be it known that I, WILLIAM P. O'HARA, of Cincinnati, Hamilton county, Ohio, have invented a new and useful Sampling-Tube or 5 Liquor-Thief, of which the following is a specification.

My invention relates to an improved construction of the device known as a "sampling-tube" or "liquor-thief," which, being inserted 10 through the bung-hole of a cask containing liquor, and liquor being allowed to flow into it is retained therein, so as to enable withdrawal of the instrument with its contents, which may then be, in part or all, delivered through the 15 lower orifice by repetition of the manipulation which permitted it to be charged.

In the accompanying drawings, Figure 1 represents a sampling-tube embodying my invention, a portion of the tube or barrel being 20 shown broken away, so as to expose the working parts. Fig. 2 is an axial section, on a larger scale, through the lower part of the instrument, the valve being shown open.

A is a tube, preferably cylindrical, and having 25 screwed onto its lower end a nozzle, B, that constitutes alternately the inlet and exit orifice of the instrument. Near the tube's lower end, and just above the said nozzle, is provided an annular seat, C, for a valve of the 30 following construction:

D is a rod or stem, which, passing through and snugly fitting a hole, e, at the center of a screw-cap, E, and having a knob, F, at its upper extremity, traverses two guide-bridges, 35 G G', within the tube, and has, near its lower end, a collar, H, and a screw-attached gland, I, between which is firmly caught a rubber or leather pad or gasket, J, which, with said members H and I, constitutes the valve proper. The 40 rubber or leather gasket J insures a tight closure of the seat C against the passage of liquor

in either direction when the valve is shut. A spring, K, secures the automatic closure of the valve whenever the stem D is relieved from the pressure of the user's thumb. A small 45 mouth-piece or "sucker," L, is provided in cap E to enable the user to expedite the charging or discharging of the instrument, as desired, by diminishing or increasing the atmospheric pressure within the tube by his lungs. 50

Projecting laterally from tube A near its top, and respectively on remote sides thereof, are a loop or bow, M, and a lip, N, that enable the user to firmly grasp the instrument with his palm and fingers while pressing with his thumb 55 upon the knob F, and also facilitate the conveyance of the instrument from place to place. The valve may be wholly metallic and rest upon a rubber seat, or valve and seat may both be wholly metallic. 60

I claim as new and of my invention—

1. The combination of tube A, automatically up-closing valve near its mouth, stem extending upwardly from the valve, having a depressing-knob, and a retracting-spring for supporting the valve to its seat, as set forth. 65

2. As a new article of manufacture, a sampling-tube, composed of tube A, nozzle B, valve-seat C, cap E, guides G G', up-closing valve, valve-rod D, and valve J, spring K, loop M, 70 lip N, and mouth-piece or sucker L, substantially as set forth.

3. In a liquor-sampling tube, the mouth-piece or sucker L, projecting exteriorly from and communicating through cap E, substantially 75 as set forth.

In testimony of which invention I hereunto set my hand.

WM. P. O'HARA.
